UNITED STATES PATENT OFFICE.

EDWARD J. MALONEY, OF LONG ISLAND CITY, NEW YORK, ASSIGNOR TO ANDREW WOLF, OF NEW YORK, N. Y.

METHOD OF FORMING STITCHES.

1,308,294.

Specification of Letters Patent.

Patented July 1, 1919.

Application filed February 27, 1914. Serial No. 821,367.

To all whom it may concern:

Be it known that I, EDWARD J. MALONEY, a citizen of the United States, and a resident of Long Island City, borough and county of Queens, city and State of New York, have invented certain new and useful Improvements in Methods of Forming Stitches, of which the following is a description in such full, clear, and exact terms as will enable any person skilled in the art to which it pertains to make and use the same.

My invention relates to a method of forming a stitch on machines for sewing straw braid in the manufacture of hats.

For a detailed description of my invention reference is now had to the accompanying drawings which represent the preferred manner of carrying out the same.

In these drawings—

Figure 1 is a view showing the work (straw braid) in section, and illustrating the construction of the stitch, the view also showing the hook and looper and illustrating diagrammatically the take-up, tension and spool and representing the position of the parts which in this specification is termed the starting or first position, and

Figs. 2 to 7 illustrate the six succeeding positions of the stitch forming devices as they occur in the operation of forming the stitch.

The hook has a point 10 to pierce the goods and a gap 11 in its front side with overhanging or undercut ends forming a double hook or chock-like orifice for the reception of the thread so that the thread is held in the hook upon the reciprocation of the same in either direction. The looper has a bill 12 to engage the loop in the thread and also has an eye 13 to receive the thread as it passes from the spool, tension and take-up. Excepting for these features particularly pointed out the parts named may be of the usual or ordinary construction and the devices for operating such parts and for imparting thereto their characteristic motions may be any of the usual cam, lever and driving devices which are commonly employed in this art to operate the stitch forming devices and which are known to and their application fully understood by persons skilled in the art.

The stitch itself is of the chain class with one side nearly blind and is a well known stitch extensively used for years in the

straw hat industry. An illustration of this stitch and of the typical devices for forming the same as heretofore employed in the practical art is to be found in the prior patent to Wilcox and Noble, No. 394,087 granted on the 30th day of October, 1888.

A description of the operation of my improved stitch forming mechanism is as follows:

(1) Starting with the parts in the position shown in Fig. 1.

(2) The hook goes down through the goods and engages the thread *b* which is held in the eye 13 of the looper.

(3) The hook goes back up through the goods taking the thread *b* through the previously formed loop *a* and through the goods forming a second loop *b* and the looper swings back casting off from its bill 12 the previously formed loop *a*.

(4) The hook steps forward from the position I to II taking the newly formed loop *b* with it.

(5) The hook again goes down through the goods taking the newly formed loop *b* down with it and the looper comes forward to meet the hook and its bill 12 engages the loop *b* and casts said loop off from the hook.

(6) The hook then goes up through the goods making at this time an idle stroke 85 since no thread is now engaged with the hook.

(7) The empty or idle hook now steps back from the position II to I and the goods are fed the length of one stitch whereupon 90 the cycle of operation is completed and the parts again take the first position, to wit, that shown in Fig. 1.

It will be observed that in this stitch forming mechanism I have dispensed with 95 one element heretofore commonly employed, namely, the needle. In fact, the machine sews without a needle, the thread in its various parts being controlled by the hook and looper. Owing to the step forward and back which the hook takes it is allowed to perform the functions jointly performed by the hook, needle and loopers of the prior stitch forming mechanism of this class which is illustrated in the above mentioned 100 patent to Wilcox and Noble. It will also be observed that the thread from the take-up and tension devices is carried in the eye of the looper and is drawn back and forth through the goods by the action of the hook 110

under the control of the tension, take-up and looper.

Having thus described my invention, what I claim as new and desire to secure by Letters Patent of the United States is:

1. The herein described method of forming a stitch through the medium of a hook and looper only, the same consisting in piercing the goods, carrying the thread back and forth therethrough by temporary engagement only of said thread with the hook, casting the loop from the hook by means permanently carrying said thread and positioning the thread for engagement by the hook to form a succeeding loop and finally drawing the thread through the first loop and through the goods.

2. The herein described method of forming a stitch, which consists in passing the thread through the goods and through a previously formed loop forming a second loop,

casting off the first formed loop, then passing the newly formed loop through the goods, and casting off the second formed loop.

3. The herein described method of forming a stitch, which consists in passing the thread through the goods and through a previously formed loop by a thread carrying member forming a second loop, casting off the first formed loop, then passing the newly formed loop through the goods, casting off the second formed loop and thence passing the thread carrying member through the goods without the thread.

In testimony whereof I have hereunto signed my name in the presence of two witnesses.

EDWARD J. MALONEY.

Witnesses:

BERTHA MEISS,
EDWARD A. WOLF.
